UNITED STATES PATENT OFFICE.

DENNIS J. DALEY, OF PITTSBURG, PENNSYLVANIA.

FOLDING FIRE-FENDER.

SPECIFICATION forming part of Letters Patent No. 352,302, dated November 9, 1886.

Application filed April 14, 1886. Serial No. 198,870. (No model.)

To all whom it may concern:

Be it known that I, DENNIS J. DALEY, a citizen of Canada, residing at Pittsburg, in the county of Allegheny and State of Pennsylvania, have invented certain new and useful Improvements in Folding Fire-Fenders; and I do hereby declare the following to be a full, clear, and exact description of the invention, such as will enable others skilled in the art to which it pertains to make and use the same, reference being had to the accompanying drawings, which form a part of this specification.

My invention is an improvement in folding fire-places, which improvement will be fully understood from the following description and claim, when taken in connection with the annexed drawings, in which—

Figure 1 is a front elevation of my improved folding fire-fender constructed in accordance with my invention. Fig. 2 is an end elevation of the same. Fig. 3 is an end elevation showing the fender folded above the fire-place. Fig. 4 is a plan view of the top of the fender. Fig. 5 is a diagram of the several movable parts of the fender to illustrate the operation of folding the same. Fig. 6 is an enlarged view of one of the joints.

To put my invention into practice I provide a narrow wire screen, *a*, of suitable length, and permanently secure the same above the fire-place, and having attached thereto about the edges a number of wire loops, *b*, which serve to hinge the same to other parts of the fender. I now provide two or more similar screens, *c*, and attach one of the same to each side of the fire-place. These sections *c* are also provided with a suitable number of wire loops, *b*, projecting from the edges, for attachment with the sides *d* of the fender. I next construct a screen, *e*, for the top, divided at the center and provided with several spring-catches, *f*, which secure the ends of the same at the dividing-line to a light round metallic rod, *g*, attached to the stationary piece *a*

above the fire-place, the other end being supported by the front of the fender. I now construct the sides *d d' d''* and front *h h' h''*, each of which is in three sections, each provided about the edge with a suitable number of projecting wire loops, *b*, through which are passed vertically and horizontally a number of metallic rods, *g*, which secure the several parts of the fender together, and form a box open at the base and the side next the fire. 50 These divided sections *h e* may be opened, for the purpose of communicating with the fire-place, without disturbing the other or main portion of the fender. When it is desired to fold the fender, the two vertical rods *g* at the 55 front and corners are withdrawn.

By referring to Fig. 5 on the drawings it will be seen that the small side sections, *d d'*, may be folded together and placed on the top section, *e*, without separation. The front sections are now folded in the same manner, and the whole swung to a perpendicular position above the fire-place, as shown in Fig. 3 on the drawings.

Having thus described my invention, what I claim, and desire to secure by Letters Patent, is—

The within-described folding fender, comprising the horizontal screen *a*, secured to the mantel above the fire-place and provided with loops *b*, adapted to serve as hinges, the vertical side screens, *c c*, also provided with wire loops, the top horizontal screen, *e*, formed of two jointed sections, provided at the joint with catches *f*, and a rod, *g*, attached to the screen *a*, the folding sides *d d' d''*, and folding front sections, *h h' h''*, said parts being connected by loops and rods, and all constructed and adapted to be folded and swung to a position above the fire-place, substantially as described. 85

DENNIS J. DALEY.
